UNITED STATES PATENT OFFICE

EMANUEL J. PERRY, OF NEW BEDFORD, MASSACHUSETTS, ASSIGNOR, BY MESNE ASSIGNMENTS, TO THE AMERICAN LAUNDRY MACHINERY COMPANY, OF NORWOOD, OHIO, A CORPORATION OF OHIO

WASHING MACHINE

Application filed November 18, 1927. Serial No. 234,106.

This invention relates to laundry machines and more particularly to machines of the so-called industrial or commercial type as distinguished from the domestic type, although it will be appreciated from the disclosure herein made that the salient features of my invention may be applied with advantage to the domestic type of machines if desired.

My invention is primarily concerned with machines of the type disclosed in my Patent No. 1,549,027 and in my copending applications Ser. No. 50,076, filed Aug. 13, 1925, and Ser. No. 119,944, filed July 1, 1926. These machines are of the self-dumping type wherein the washing cylinder may be moved by power from its normal position within the casing to a position outside of the casing for discharging the contents therefrom. For effecting this movement of the cylinder out of the casing and its return thereinto, these machines make use of gear sectors pivotally mounted on the machine frame and having journal bearings for the cylinder shafts. These sectors are engaged by driving gears which may be rendered effective or ineffective either by altering the transmission apparatus between such gears and the prime mover or by direct control of the prime mover itself. In either case, it is apparent that the duration of the operating period of the sector driving gears must be accurately controlled in order to avoid undesirable strains or injury to the sectors and their associated mechanism. It has been found in practice that manual control of this operating period is unreliable and it has also developed that automatic mechanisms may by reason of wear or unauthorized adjustment become unreliable, the result in either case being breakage of parts which are essential to the operation of the machine.

It is also apparent that in this type of cylinder elevating mechanism, the full load is imposed on the motor or other prime mover immediately upon its being placed in operation, or being operatively connected with the sector driving gears. This fact necessitates the use of a larger and consequently more expensive motor or other prime mover, in order

to obtain the required high starting torque, than would otherwise be necessary.

The imperfections outlined in the preceding paragraphs are a source of trouble, inconvenience and expense in all sizes of this type of machine, but more particularly in the extremely large industrial machines wherein the weight and inertia of the moving parts of the machine greatly magnify the danger due to such imperfections.

The general object of my invention, therefore, is to provide a machine having all of the merits and advantages of my prior machines, but without the imperfections outlined above.

More specifically, it is an object of my invention to provide a self-dumping type of laundry machine wherein it will be impossible for the cylinder to exceed its normal limit of movement in either direction.

A further object of my invention relates to the provision of means whereby the prime mover is permitted to build up a substantial torque before assuming the load incident to the cylinder elevating operation.

A still further object resides in the provision of a cylinder elevating mechanism wherein the load is gradually assumed by the prime mover.

It is also an object of my invention to provide a mechanism for opening the cover of the machine casing in combination with my improved cylinder elevating mechanism.

Further objects relate to structural details and combinations thereof, all of which will be more specifically pointed out hereinafter.

In the drawings:

Fig. 1 is a rear elevation of my improved machine,

Fig. 2 is a view in end elevation showing cylinder in position within the casing,

Fig. 3 is a view similar to Fig. 2 but showing the cylinder in dumping position, and,

Fig. 4 is a view partly in vertical section illustrating a portion of the driving mechanism.

The general structure of my invention embodies a cylindrical casing 1 which may be supported by a plurality of base members 2. The casing 1 is provided with a cover 3 which

may be hinged as indicated at 4 to the rear side of the casing. The cylinder 1 and cover 3 are provided with complementary semi-circular openings which together afford an opening through which the cylinder shafts 7 are adapted to pass. The cylinder 8 is journaled in the ends of arms 9 which are pivotally mounted on the machine casing as indicated at 10. By means of this disposition of the cylinder it may be moved from its normal position within the casing to an upper and outer position, as illustrated in Fig. 3 of the drawings, wherein the contents of the cylinder may be readily discharged. By inspection of Fig. 1 it will be noted that the pivotally mounted arms 9 lie adjacent the outer side of the end walls of the cylinder and carry the extremities of the cylinder shafts 7.

20 In order to automatically move the casing cover 3 to open position in timed relation with the elevating of the cylinder I have provided a mechanism which comprises a cam member 16 secured to the gear 11 and adapted to co-act with a cam follower 18 having a roller 17 for engagement with the peripheral cam surface. The movable member 18 is slidably mounted in a guide member 21 secured to the end wall of the casing and is operatively connected to the cover by means of link 19 which is pivotally connected with the cover at 20. It will be observed that a major portion of the circumference of the cam member is concentric with the axis of shaft 12 and by virtue thereof the cover 3 is maintained in open position during a substantial portion of the revolution of the gear 11. The cam is of such a contour as to rapidly open and close the cover.

40 My improved cylinder elevating mechanism is best illustrated in Figs. 2 and 3 wherein the cylinder together with its operating mechanism is shown in its two active positions. The end walls of the casing 1 are provided with shafts 12 on which gear elements 11 are journaled. It will be noted that the axes of shafts 12 are substantially directly beneath the axis of the cylinder, although slightly to one side of a vertical plane passing through the cylinder axis. The combined gear and crank disk 11 is provided with a crank pin 14 which coacts with an elongated slot formed in the corresponding end of the connecting link 13. The opposite end 55 of link 13 is pivotally connected as at 15 to the arms 9 substantially midway of their length. By virtue of this construction it will be apparent that upon rotation of the gear 11 the lost motion afforded by the elongated slot will be gradually taken up and movement will be imparted from the crank pin 14 through link 13 to the arms 9 for moving such arms about their pivots 10 and thus raising the cylinder from its position within the casing to substantially the position shown in

Fig. 3. The function of the lost motion connection as described is to permit the prime mover to get under way and build up a substantial operating torque before the load of the cylinder is imposed upon it. In this connection it will be noted that in the normal position of the parts illustrated in Fig. 2, the centers of the crank pins 14 and 15 and the center of the shaft 12 are in exact alinement with the center of shaft 12 between the two crank pins, while in the position of the parts illustrated in Fig. 3, the centers of the three elements are still in alinement but the crank pin 14 has moved to a position on the opposite side of shaft 12. This construction, that is the gear 11 and the link 13 connected thereto by the pin 14 and the slot with the variations in leverage produced by these coacting elements as they assume different relative positions or angles during normal operation, affords a variable leverage drive between the prime mover and the cylinder elevating arms whereby the load incident to the elevating operation is imposed upon the motor in a gradual manner.

The mechanism for rotating the cylinder is quite simple and in the present construction embodies large gears 22 at opposite ends of the cylinder and secured to the shafts 7, which gears are at times adapted to mesh with driving gears 23 which are rotatably and slidably mounted on a longitudinally disposed shaft 24. A second longitudinally disposed shaft 33 is journaled in the frame of the machine directly beneath the motor support and is permanently geared to the motor shaft through the gears 34 and 35 as clearly shown in Figs. 1 and 4. This shaft 33 is provided at each end with a wide faced pinion 32 which is positioned to engage the gears 23. It is noted that pinions 32 are of sufficient width to maintain driving engagement with the gears 23 even when the latter gears are shifted out of engagement with the cylinder gears 22. It is apparent, therefore, that there is a constant driving connection from the motor 37 to the gears 23 and that these gears may be shifted at will into or out of engagement with the large gears 22 carried by the cylinder. The shifting movement of the gears 23 has a function in addition to that of disconnecting the cylinder drive, which function will be hereinafter pointed out.

Journalized in the machine frame adjacent the lower portion thereof and on the rearward side is a longitudinally disposed shaft 26 which has secured at its opposite ends pinions 25 in permanent meshing engagement with the cylinder elevating gears 11. This shaft 26 is connected to be driven from shaft 24 through a reduction gearing consisting of intermeshing beveled gears 30 and 31, shaft 29, and worm wheel and worm 27 and 28 respectively. The worm gearing is pro-

vided with a housing 40' which may be formed as a part of an intermediate supporting member 2. The shaft 29 is supported at its upper end by a bracket 41 which is secured to the machine frame. It will be observed that during rotation of the cylinder, the shaft 24 is inactive. In order to bring the shaft 24 into operation I have arranged the transmitting devices in such a manner as to require the disconnection of the cylinder driving mechanism. This is accomplished by mounting the gears 23 loosely upon the shaft 24 and providing one or both of said gears with shifting collars 38 and clutches 39, the latter being adapted to coact with the clutch collar 40 secured to the shaft 24. In this way, it will be seen that by shifting the gears 23 out of engagement with the cylinder driving gear 22, the clutch elements 39 and 40 are brought into engagement and inasmuch as constant meshing engagement is maintained between the gears 23 and pinions 32, an operative connection is established from the motor to the shaft 24 which in turn operates through the reduction gearing to drive shaft 26 and the cylinder elevating mechanism associated therewith. Any desired form of lever mechanism may be provided for simultaneously shifting the gears 23. The gearing connecting the motor shaft 36 and transmission shaft 33 may be closed by a suitable housing 38 having a removable cover 39.

The operation of my improved construction should be apparent from the above disclosure but for the sake of clearness may be briefly reviewed as follows:

With the parts given the position illustrated in Fig. 2, the motor 37 may be energized and allowed to operate for any desired period for carrying out the washing operation. It will be understood that this motor is of such a type and is provided with suitable circuit controlling means whereby an alternating rotary motion is imparted to the washing cylinder. At the expiration of the washing operation, it is desired to remove the cylinder from the casing, discharge the contents thereof and then replace the cylinder within the casing for a second washing operation. To accomplish this operation, it is merely necessary to break the motor circuit (not shown), shift the gears 23 out of engagement with cylinder gears 22 and thereby effect a coupling between the gears 23 and shaft 24 and consequently effect operative connection from the motor to the shaft 26. The motor may now be energized and permitted to operate for a predetermined period which may be controlled by suitable timing mechanism in order to elevate the cylinder out of the casing. In this connection it will be noted that the inward and outward limits of movement of the cylinder are positively limited by the alignment of the axes of move-

ment of certain of the mechanical elements which produce such movement at predetermined intervals of a complete cycle of operation and for this reason it is apparent that an overthrow of the cylinder in either direction cannot be caused by any failure or inaccurate adjustment of the timing mechanism which controls the motor circuit. Moreover it is important to note that by reason of the lost motion connection provided at the crank pin 14, the motor is permitted to build up a starting torque before assuming the load and for this reason it is possible to use a smaller and cheaper motor. The motor is further assisted in the work of elevating the cylinder by reason of the variable leverage connections above described between the gear 11 and arms 9.

The structure herein described has been found exceptionally adapted to the carrying out of the objects of my invention as outlined herein, but it will be appreciated that many changes and substitutions might be made without altering the advantages or operation of the resulting structure or departing from the spirit of the invention. I therefore desire it understood that the specific disclosure herein made is to be construed merely as an illustration of one form which my invention may take and not in any sense a limitation thereon.

What I claim is:

1. In a laundry machine, the combination with a casing and a washing cylinder therein, of means for moving said cylinder out of and into said casing, said means comprising a prime mover and a lost motion connection between said prime mover and cylinder moving means to cause said prime mover to develop a substantial torque before assuming any of the load.

2. In a laundry machine, the combination with a casing and a washing cylinder therein, of means for moving said cylinder out of and into said casing, said means comprising a prime mover and combined variable leverage and lost motion connections between said cylinder and prime mover.

3. In a laundry machine, the combination with a casing and a washing member movably disposed therein, of pivotally mounted arms connected at opposite ends to the casing and said washing member and movable to carry said member out of or into said casing according to the direction of such movement, and means for moving said arms including a rotatable member, a crank carried by said rotatable member and a link at one end connected by a lost motion connection to said crank and at its other end connected to one of said arms.

4. In a washing machine, the combination with a casing and a washing member movably disposed therein, a hinged cover for said casing, of pivotally mounted arms on said

- casing whereby said washing member is mounted and movable to carry said member out of or into said casing according to the direction of said movement, means for moving 5 said arms including a rotatable member on said casing, a crank connected to said rotatable member and a link connecting said crank and one of said arms, and means for raising and lowering said cover including a cam 10 carried by said rotatable member, a cam follower, and connections between said cam follower and said cover.
5. In a laundry machine, the combination with a casing, of arms pivotally mounted on 15 said casing, a washing cylinder journaled on said arms and movable therewith in an arcuate path into and out of said casing, a prime mover, mechanical connections between said prime mover and one of said arms for operating the latter and including as an operative 20 part of said connections means for positively limiting the movement of said arms in both directions.
6. In a laundry machine, the combination 25 with a casing, of arms pivotally mounted on said casing, a washing cylinder journaled on said arms and movable therewith in an arcuate path into and out of said casing, a prime mover, mechanical connections between 30 said prime mover and one of said arms for operating the latter, said connections including a crank pin moved by the prime mover through a complete circle for positively limiting the movement of said arms in both 35 directions when reaching its opposite dead centers and a link having a lost motion connection with said crank pin to enable said prime mover to develop a starting torque before assuming the load.
- 40 7. In a laundry machine, the combination with a casing, of arms pivotally mounted on said casing, a washing cylinder journaled on said arms and movable therewith in an arcuate path into and out of said cylinder, and 45 means for moving said arms including a crank disk journaled on said casing having a crank pin thereon, a crank pin on one of said arms, a link connecting said crank pins and a lost motion connection between said link 50 and one of said crank pins.
8. In a laundry machine, the combination 55 with a casing of arms pivotally mounted on said casing, a washing cylinder journaled on said arms and movable therewith in an arcuate path into and out of said casing, and means for moving said arms including a crank disk journaled on said casing having a crank pin thereon, a crank pin on one of 60 said arms and a link connecting said crank pins, said disk, link and crank pins being so arranged that with the arms at their limits of movement, the centers of said disk and crank pins lie in a common straight line.
- 65 9. In a laundry machine, the combination 70 with a frame supported casing and a wash- ing cylinder rotatably and removably dis- posed therein, a gear carried by said cylinder, a pair of shafts journaled in said frame, means connecting said cylinder and one of 75 said shafts for moving said cylinder into and out of said casing, a gear journaled on the other said shaft and adapted to drive said cylinder gear, reduction gearing connecting the two said shafts, a prime mover operatively connected to said journaled gear, said journaled gear being supported for shifting movement into and out of operative connection with said cylinder gear, and means operative upon movement of said journaled gear out of operative relation with said cylinder gear for coupling said journaled gear and last mentioned shaft whereby to establish power transmitting connection between said prime mover and said first mentioned shaft.
10. In a laundry machine of the type em- 80 bodying a frame structure having a supporting base for a cylindrical casing and a motor support disposed at the rear of and adjacent the top of the machine and having a cylindri- 85 cal casing on said supporting base, a cylind- er rotatable and removably disposed within said casing, and means for operating said cylinder comprising a motor on said support, a shaft disposed longitudinally of the ma- 90chine and journaled in said frame, gearing 95 connecting said motor and said shaft, a wide faced pinion secured to said shaft, a second shaft journaled in said frame parallel to said shaft, a gear rotatably and slidably disposed on said second shaft and in meshing engage- 100ment with said wide faced pinion, means con- 105 nected to said cylinder operable by said gear when in one position for rotating said cylin- 110 der, a third shaft journaled in said frame parallel to the other said shafts, means op- 115 erated by said third shaft for moving said cylinder into and out of said casing, a coun- 120ter shaft and reduction gear connecting said second and third shafts and means operative upon shifting of said rotatably and slidably mounted gear out of operating relation with the means connected to said cylinder for cou- 125pling said gear to said second shaft whereby to complete the driving connection between said motor and said third shaft.
11. In a laundry machine, the combination 130 with a casing having a washing cylinder ro- tatably and removably disposed therein, of a gear journaled on an end of said casing, connections between said gear and cylinder 135 for moving the latter into and out of said casing, a hinged cover for said casing, and means for opening and closing said cover during certain movements of the cylinder in- 140cluding a cam secured to said gear, a guide 145 secured to said casing end adjacent said cam, a cam follower disposed in said guide and co- 150operating with said cam and a link connect- 155ing said cam follower with said cover.
12. In a laundry machine, the combination 160 with a frame supported casing and a wash-

with a casing having a washing cylinder rotatably and removably disposed therein, arms pivotally mounted on said casing and having said cylinder journaled thereon, a hinged 5 cover for said casing, and means for simultaneously operating said arms and cover including a gear journaled on an end of said casing, a crank pin carried by said gear, a crank pin carried on one of said arms, a link 10 connecting said crank pins, a cam driven by said gear, a guide secured to said casing end adjacent said cam, a cam follower disposed in said guide and coacting with said cam and a link connecting said cover and cam follower. 15

In testimony whereof I affix my signature.
EMANUEL J. PERRY.
